UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON STOCK.

Application filed September 15, 1920, Serial No. 410,443. Renewed June 23, 1925.

To all whom it may concern:

Be it known that I, ERASTUS E. WINKLEY, a citizen of the United States, residing at Lynn, in the county of Essex and State of Massachusetts, have invented certain new and useful Improvements in Machines for Operating Upon Stock; and I do hereby declare the following to be a full, clear, and exact description of the invention, such as will enable others skilled in the art to which it appertains to make and use the same.

This invention relates to machines for operating upon stock, and more particularly to stock-cutting or "dinking" machines such as those employed for producing heel lifts.

Machines for operating upon stock are frequently adapted to perform a series of successive operations upon a strip or sheet of material as the latter is intermittently fed to the operating instrumentalities of the machine. In machines of this character, the first and last operations performed upon each piece of stock are likely to result in the production of imperfect work. In stock-cutting machines, for example, which operate to cut blanks successively from a strip of stock an imperfect or incomplete blank will be cut from the leading end of the stock if the stock is improperly positioned for the first cutting operation, and the last cutting operation will also produce an imperfect blank unless the strip of stock was originally of such length that no waste end remains after the last perfect or full sized blank has been cut therefrom. Accordingly it is desirable to make special provision for preventing the production of imperfect work at both the forward and rear ends of the material operated upon.

The object of the present invention is to reorganize and improve machines of the above named general character for the purpose of rendering them more efficient and reliable in operation, and insuring that the results of operations performed at the front and rear ends of each piece of material operated upon shall be uniform with the results of operations performed throughout the length of the intermediate portion thereof.

With this object in view, one feature of the invention contemplates the provision, in a machine for operating upon stock, of

initially idle operating mechanism, and means for rendering said mechanism operative to perform a succession of operations upon the stock only when the stock has been properly located for the first operation to be performed upon it, thereby insuring that said first operation will be properly performed.

To prevent the production of imperfect work at the rear end of each piece of stock, and to insure that the operating mechanism shall be idle while a succeeding piece of stock is being fed into position for the performance of the first operation thereon, a further feature of the present invention comprises the provision, in a machine of the character specified, of improved means for determining the state of exhaustion of the stock and for automatically stopping the action of the operating instrumentalities when the piece of stock being operated on has become so far exhausted that there is not enough left to permit another operation to be properly performed thereon.

The invention further consists in the features of construction and combinations and arrangements of parts hereinafter described and subsequently defined in the appended claims, the advantages of which will be apparent to those skilled in the art.

The various features of the invention will be readily understood from the following description and the accompanying drawings in which the invention is illustrated, in its preferred form, as embodied in a heel lift cutting or "dinking" machine.

In the drawings, Figure 1 is a plan view of the machine; Fig. 2 is a perspective view of a portion of the mechanism for locating the stock for the first cutting operation and for starting the operation of the cutting-block; Fig. 3 is a view in side elevation looking from the right in Fig. 1, certain parts being broken away to disclose parts of the operating mechanism otherwise obscured; Figs. 4 and 5 are plan views, on an enlarged scale, of portions of the machine located at the right and left sides, respectively, of the central vertical plane extending through the cutting instrumentalities; Fig. 6 is a detail view, in side elevation, of the cooperating die and cutting-

block showing also the die-stripper and the discharge platform; Fig. 7 is a sectional view on the line 7—7 of Fig. 6; Fig. 8 is a view in central vertical section of the parts shown in Fig. 6; Fig. 9 is a vertical sectional view taken on a plane between the die and the cutting-block, looking toward the front of the machine; Fig. 10 is a perspective view of the various cams and the driving mechanism as seen from the rear of the machine; Fig. 11 is a perspective view showing portions of the stock feeding mechanism and the feeler mechanism for detecting critical exhaustion of the stock; Fig. 11^a is a view of a portion of a sheet of stock illustrating the operation of the cutting instrumentalities; Fig. 12 is a view, in side elevation, of a portion of the machine looking from the left in Fig. 1 and showing particularly the cam shaft together with its several cams and parts actuated thereby; Fig. 13 is a view in vertical section taken on a plane extending through the cam shaft, looking toward the rear of the machine; Fig. 14 is a detail view, in vertical section, of the plunger that carries the cutting-block; Fig. 15 is a detail perspective view of a portion of the actuating mechanism for the cutting-block; Fig. 16 is a vertical sectional view taken on a plane between the die and the cutting-block, looking toward the rear of the machine; Fig. 17 is a view, in side elevation and on an enlarged scale, of a portion of the machine shown in Fig. 3; Fig. 18 is a plan view illustrating particularly the clutch for actuating the cam shaft, a portion of the mechanism for controlling the operation of the clutch and a portion of the mechanism for preventing the butting of strips or pieces of stock; and Fig. 19 is a plan view illustrating particularly the various cams and the parts directly actuated thereby.

The present invention is illustrated as embodied in a lift-cutting machine which is adapted to feed sheet material in a vertical plane to the cutting instrumentalities. The latter comprises a stationary die 24 (Fig. 1) which is mounted with its cutting edge disposed in a vertical plane, and a vertically disposed cutting-block 26 which is adapted to reciprocate horizontally toward and from the die to cut lifts successively from the stock as the stock is advanced between the die and the cutting-block. The die 24 is open at both ends to permit the lifts cut by the die to pass through the die and be discharged therefrom in stacked formation. The cutting-block 26 is caused to remain inoperative while each piece of stock is being fed into position for the first cutting operation, and is adapted to be actuated only when the leading end of the stock has been fed completely across the die so that the cutting of a perfect first lift will be insured. When the stock which is being operated upon

has been so far exhausted that there is not enough left to produce another complete lift, the cutting-block 26 is automatically disconnected from its actuating mechanism to prevent the cutting of scrap into the die, and provision is made for discharging the remaining waste portion of the stock from the line of feed of a succeeding piece of stock.

The operating parts of the machine are carried by a head 28 (Figs. 1 and 3) which is supported by a pair of brackets 30 projecting upwardly at the front and rear of the machine from a pair of standards 32, the latter being connected together at opposite sides of the machine by means of cross-bars 34. A vertical main shaft 36 is journaled in suitable bearings in the head 28 and is connected by intermeshing bevel gears 38 (Fig. 3) with a horizontal shaft 40 which is journaled in bearings in the cross-bars 34 and is provided with the usual fast and loose pulleys 42 and 44. Journaled in bearings in a pair of brackets 46 which are bolted to the head 28 is a vertical shaft 48 (Figs. 1, 5, 10, and 13) having secured thereto a cam 50 which periodically actuates a feeler 52 that operates, upon critical exhaustion of the stock, to render the cutting mechanism inoperative. The vertical shaft 48 is continuously driven, during the operation of the machine, through a train of gearings comprising a spur gear 54 on the main shaft 36, an idler gear 56 that is pivotally mounted upon the head 28, and a spur gear 58 that is secured to the lower end of the vertical shaft 48. Loosely surrounding the shaft 48 is a sleeve 60 (Figs. 10, 12 and 13) carrying a plurality of cams 62, 64, 66 and 68 which actuate certain of the various component mechanisms of the machine in proper timed relation with each other, as will be hereinafter set forth. The cam sleeve 60 is normally idle, but is adapted to be connected to rotate with the vertical shaft 48 by means of clutch mechanism 70 (Figs. 10, 12 and 13). The operation of the clutch mechanism 70 is controlled by devices which are in turn controlled by the piece of stock which is being operated upon. The various levers which cooperate with the several cams for actuating the component mechanisms of the machine are mounted upon the head 28.

The stock is cut by means of the die 24 which is arranged with its breast edge uppermost and is suitably secured in place upon a die-holder 74, as shown in Figs. 1 and 3. The die-holder 74 is substantially circular in outline and is provided with a concentric circular shoulder 76 which is seated in a circular opening in the head 28. The die-holder 74 is further provided with a beveled clamping plate 78 (Fig. 3) that is adapted to be engaged by the correspond-

ingly beveled end of a clamping yoke 80 which is held in clamping position on the head 28 by means of a screw 82. A horizontal chute 84 (Fig. 3) is connected with 5 the die so that the die and the chute form a continuous guideway through which the lifts are forced in stacked formation. With this arrangement the lifts may pass from the die into and through the chute 84 without danger of being jammed and may be 10 removed from the chute in stacked relation with facility.

In order to adapt the machine to produce different sized lifts, provision is made for 15 mounting dies of different sizes in the head 28. It is desirable that the different sized dies shall be so positioned in the machine that irrespective of the size of the die the upper cutting edge at the breast of the die 20 will always be located at the same level and the position of the lateral cutting edge first reached by the stock will always be located at the same point in the path of feed of the stock. To this end it is contemplated 25 that dies of different sizes for use in the machine shall be severally mounted upon a plurality of interchangeable die-holders before the holders are furnished to the operator of the machine, each die being so positioned 30 on its holder relatively to the center of the holder that when any one of the die-holders is clamped in position in the machine the die carried thereby will be located with the above mentioned portions of its 35 cutting edge located in the required positions.

The cutting-block 26 is of a rectangular form and is mounted in a holder 88 that is carried at the forward end of a hollow plunger 90 (Figs. 1, 4 and 5). The cutting-block 26 is removably mounted in the holder 88, and the holder 88 is adjustably secured to the plunger 90, the construction and arrangement of these parts being substantially 40 the same as that of corresponding parts illustrated and described in a co-pending application, Serial No. 371,725, filed April 6, 1920, by the present applicant, and assigned to the United Shoe Machinery 45 Corporation (now Patent No. 1,454,877 granted May 15, 1923). Inasmuch as the cutting-block becomes grooved by reason of its cooperation with the cutting edge of the die, it is desirable, in practice, to provide a separate cutting-block for each die 50 which is employed in the machine, and when a die of a different size is placed in the machine, a different cutting-block will also be placed therein. The plunger 90 is adapted 55 to reciprocate within a bearing 92 at the top of the machine but at the start of operations upon a strip of stock the plunger is disconnected from its actuating mechanism so that the cutting mechanism is maintained inoperative.

The cutting-block 26 is advanced toward the die by means including an eccentric pin 96 (Figs. 1, 10 and 15) which projects from the upper end of the main shaft 36. The eccentric pin 96 serves to reciprocate a pitman 98, to the bifurcated forward end of which is pivotally connected a push bar 102, of an irregular shape best shown in Fig. 15, and which is adapted to operatively connect the pitman 98 with the plunger 90. During the feeding of a piece of stock into position for the first cutting operation however, the pitman 98 and the push bar 102 reciprocate idly, but when the leading end 70 of the stock has been fed completely across the die, the pitman and the push bar are rendered operative automatically to actuate the plunger 90 and the cutting-block 26. The rear of the plunger 90 is hollow to receive the push bar and the forward end of the pitman, and in order to guide the pitman as it reciprocates, a pair of slide-blocks 104 (Fig. 15), which are carried at the forward end of the pitman, are received in a pair of longitudinal guideways 106 (Fig. 80 10) in the inner side walls of the hollow plunger 90. The push bar 102 is acted upon by a leaf spring 108 which is secured to one side of the pitman and tends to swing the pivoted push bar 102 to position 85 its forward end opposite a lug 110 (Figs. 4 and 5) which projects from the base of the recess in the plunger 90. At the start of operations of the machine, the link 102 is 90 held at one side of the lug 110, in the position shown by dotted lines in Fig. 1, by means of a rod 112 (see also Fig. 5) the operation of which will be hereinafter described. When thus inoperatively positioned, the push bar 102 reciprocates idly 95 within a longitudinal slot 114 in the side wall of the plunger 90. The rod 112 is adapted to be automatically withdrawn to permit the spring 108 to swing the push bar 102 to bring its forward end opposite the lug 110 in order that it may operate, as it moves forward, to advance the plunger 90 and the cutting-block. Upon the rearward movement of the push bar 102, a coiled 100 spring 114 (Fig. 1) one end of which is secured to the plunger 90 and the opposite thereof to the bearing 92, moves the plunger 105 and the cutting-block rearwardly.

The stock from which the lifts are to be 110 cut is introduced into a guideway 118 (Figs. 1 and 4) in which the stock is supported in a vertical plane while it is being acted upon by the feed mechanism, the lower longitudinal edge of the stock resting upon a stationary supporting platform 120. The guideway 118 is formed between two parallel side walls 122 and 124 which are horizontally disposed at the right hand side of the machine with their inner ends adjacent 125 the main feeding mechanism 52. The front 130

- side wall 122 is supported by a bracket 126 which is bolted to the frame of the machine, and the supporting platform 120 is rigidly but adjustably secured to this side wall.
- 5 The platform 120, as shown in Fig. 3, comprises a strip of angle iron arranged with one web horizontally disposed to support the lower edge of the stock, while the other web is vertically disposed and secured to the rear of the side wall 122 by means of bolts 127 extending through vertical slots in said web. This construction permits vertical adjustment of the platform 120 in accordance with the size of the die employed
- 10 so that the lower edge of the stock will be supported in line with the lowermost point of the cutting edge of the die. The rear side wall 124 of the guideway 118 is supported by means of suitable angle iron castings 128, each having a horizontally disposed web which is secured to the platform 120, and a vertically disposed web which is secured to the rear of said side wall.
- 15 The stock supported in the guideway 118 is fed to the cutting mechanism by means of a pair of toothed or roughened feed rolls 134 and 136 (Figs. 3, 11, 16 and 18) which constitute a portion of the main feed mechanism. The feed rolls 134 and 136 are fastened upon vertical shafts 138 and 140, respectively, which are provided at their lower ends with gears 142 and 144 (Figs. 3 and 4), these gears meshing, respectively, with pinions 146 and 148, the pinion 148 being driven from the pinion 146, and the pinion 146 being driven from a gear 150. The gear 150 is secured to the upper end of a short vertical shaft 152 which is journaled in bearings in a bracket 154 that is belted to the head 28.
- 20 To provide for relative movements of approach and separation of the feed rolls 134 and 136 in order to accommodate stock of varying thicknesses without disturbing the connection between the gears 142, 144 and the pinions 146, 148, the feed roll shafts 138 and 140 are mounted in bearings formed in supporting arms 156 and 158, respectively, (Fig. 4), said bearings being arranged
- 25 to swing about the axes about which the pinions 146 and 148 turn. The feed rolls are yieldingly pressed toward each other by means permitting adjustment of their limit of approach, and provision is made for normally maintaining the feed rolls at their adjusted limit of approach and for permitting them to separate yieldingly in order to accommodate different thicknesses of stock or variations in the thickness of the material
- 30 being acted upon. The means employed for effecting the above results is substantially the same as that illustrated and described in United States Letters Patent No. 1,291,726, granted January 21, 1919, to W. C. Baxter,
- 35 and assigned to the United Shoe Machinery

Corporation, to which reference may be had for a full and complete understanding of the construction and operation thereof.

In order that the stock may be intermittently fed, the gear 150 is rotated by means of a ratchet-and-pawl mechanism which is actuated by means of a crank pin 160 (Figs. 16 and 19) projecting from the lower side of the gear 58 on the vertical shaft 48. The ratchet-and-pawl mechanism comprises a ratchet-wheel 164 (Figs. 3, 11 and 19) and a driving pawl 166, carried by an arm 168, that is mounted to oscillate freely on the shaft 152, the driving pawl being secured to the lower end of a stud 170 which is free to turn in the outer end of the arm 168. For a purpose which will be hereinafter explained, the pawl-carrying arm 168 is connected with its actuating mechanism through a yielding coupling, one member of which consists of a segmental arm 172, which is secured at one end to the stud 170 on the opposite side of the pawl-carrying arm 168 from the pawl 166. The segmental arm 172 is provided on its inner peripheral face with a notch 174 of the shape shown in Fig. 19. Normally seated in the notch 174 is a roller 176 that is carried by an arm 178 which is also adapted to oscillate freely on the shaft 152. The weight of the segmental arm 172 normally maintains it in such a position that the roll 176 engages the notch 174, and the pawl 166 operatively engages the teeth of the ratchet-wheel 164. The arm 178 is connected by means of a pitman 180 with the crank-pin 160 on the gear 58. By means of the above described construction the pawl-carrying arm 168 is normally oscillated throughout its maximum stroke to impart a feed movement of predetermined length to the stock, but if for any reason the advance of the stock is obstructed, the roll 176 rides out of the notch 174 in the segmental arm 172 and the remainder of the stroke of the arm 178 is idle, the roll 176 riding across the inner peripheral face of the segmental arm. When the roll 176 thus engages the inner peripheral face of the arm 172, the arm will be tilted upwardly to retract the pawl 166 from the teeth of the ratchet-wheel 164 so that the pawl, upon its return stroke, will not tend to rotate the ratchet-wheel. During the return movement of the arm 178 after the roll 176 has been disengaged from the notch 174, the roll 176 will ride idle across the inner peripheral face of the segmental arm 172 until it encounters the notch 174, whereupon it will enter the notch and through the arm 172 will positively restore the pawl-carrying arm 168 into position for its next feed movement. As shown in Fig. 12, the crank-pin 160 by means of which the pitman 180 is reciprocated, is carried, as in the Baxter patent hereinbefore referred to, upon a sliding block that is mount-

ed in a guideway extending along the radius of said gear, and said block is adapted to be adjusted in the guideway to vary the throw of the pitman 180, and thereby the amount of turning of the gear 150 when it is desired to vary the amount of feed movement imparted to the feed mechanism. Before starting the operation of the machine the position of the crank pin 160 on the gear 58 is adjusted so that the length of feed imparted to the stock will be equal to the width of the particular die which is to be employed plus the width of a narrow strip of scrap which is to be left between the cuts in the stock, as shown in Fig. 11^a.

In order to adapt the machine to operate upon sheet stock, a pair of corrugated cutting disks 188 and 190 are secured to the upper ends of the shafts 138 and 140, respectively, which carry the feed rolls. The cutting disks 188 and 190 serve to separate a strip of material from which the lifts are immediately to be died from the lower portion of a sheet of stock as the cutting operation progresses. The cutting disks overlap, as shown in Fig. 1, and cut the stock with a rotary shearing action as is in the machine of the aforesaid Baxter patent. The manner in which a strip is separated by the cutting disks from a sheet of stock is illustrated in Fig. 11^a, in which the line of cut made by the disks is indicated at 186.

After advancing beyond the feed rolls the stock is fed across a die-stripper 192 (Figs. 1, 6, 7 and 8) and then passes between the die and the cutting-block. The die-stripper 192 comprises an arm rising vertically between the die and the feed rolls, and having a stock-engaging face normally positioned in a vertical plane slightly at the rear of the cutting edge of the die. The die-stripper arm is secured at its lower end to a slide-block 194 (Figs. 6 and 8) which is adapted to slide forwardly and rearwardly upon a horizontal face 196 on the head 28. The slide-block 194 is guided in its sliding movements by means of a pair of guide rods 198 projecting forwardly from the slide-block and extending into recesses 200 in the head 28. Surrounding each guide rod 198 is a coiled spring 202, one end of which bears against the front vertical face of the slide-block, while the opposite end thereof engages a vertical face formed on the head 28, opposite the slide-block. The spring 202 normally maintains the die-stripper in the position in which it appears in Figs. 6 and 7, with its stock-engaging face disposed rearwardly of the cutting edge of the die. As the cutting-block cooperates with the die the stock is displaced forwardly while a lift is being cut therefrom, and the die-stripper is correspondingly displaced by the stock, against the force of the spring 202. Upon movement of the cutting-block away from

the die, the die-stripper is moved rearwardly by the spring 202 and strips the stock from the die.

In order to prevent the leading end of the stock from striking against the die-stripper as the stock advances beyond the feed rolls, means is provided for guiding the portion of the stock extending between the feed rolls and the die-stripper. This means comprises a pair of guide fingers 206 and 208 (Figs. 1 and 4) which yieldingly engage opposite sides of the stock. The guide finger 206 is pivoted at one end upon a stud rising from a bracket 210 (Fig. 4) which is rigidly but adjustably secured to the rear side wall 124 of the guideway 118, by means of a bolt 211 which extends through a vertical slot in said bracket. When the stock supporting platform 120 is adjusted vertically the side wall 124 is necessarily adjusted therewith. The vertical slot in the bracket 210 permits said adjustment to be made, when the bolt 211 is loosened, without changing the elevation of the guide finger. The guide finger 206 extends through a groove in the side wall 124 of the guideway 118 and through a transverse annular groove in the feed roll 134, the finger terminating at a point adjacent the near side of the die and at the rear of the die-stripper. As shown in Fig. 4, the length of the guide finger is such that the finger will not interfere with the reciprocation of the cutting-block. The guide finger 206 is acted upon by a coiled spring 212 which tends to oscillate the finger about its pivot stud so as to urge the free extremity of the finger forwardly into the guideway 118. To this end the spring 212 is secured at one end to a lug 214 projecting forwardly from the finger 206, while at its opposite end the spring is secured to the rear side wall 124 of the guideway 118. The guide finger 208, which cooperates with the guide finger 206 to direct the stock across the die-stripper and the die, is connected, at the end remote

from the feeding mechanism, to a member 216 (Fig. 1) that is pivotally mounted upon the outer side of the front side wall 122. The guide finger 208 extends close to the outer side of the side wall 122 to a point substantially opposite the pivot stud upon which the guide finger 206 is mounted, and from this point the finger 208 curves rearwardly through a slot in the side wall 122 and into the guideway 118 where, if no stock is present, the two guide fingers engage each other at a point in the common axial plane of the feed rolls. At this point the guide finger 208 is received in a transverse annular groove in the feed roll 136, and thence it extends in parallelism with its cooperating finger to the free end of the latter. To press the guide finger 208 toward the guide finger 206 to yieldingly engage and guide the stock, the guide finger 208 is acted upon by

6
a coiled spring 218 (Fig. 4) which surrounds a stud 220 projecting forwardly from the stationary side wall 122, one end of the spring bearing against the guide finger 208, and the opposite end of the spring against a nut 222 on the stud 220 which may be adjusted to vary the compression of the spring.

As the stock advances beyond the die-stripper 192, its leading end is supported 10 upon a movable platform 226 (Figs. 6, 7, 8 and 17). This platform 226, being located in the vertical plane of the stock and in a horizontal plane just beneath the lowermost portion of the cutting edge of the die, lies 15 in the path of movement of the cutting-block as the latter advances toward the die. The platform 226 is so mounted that it may be laterally displaced toward the front of the machine at each advance of the cutting-block to permit the latter to cooperate with 20 the die. Under certain conditions, also, the platform 226 performs a die-stripping function, as it returns to normal strip-supporting position, after being laterally displaced 25 therefrom. In addition to being laterally displaced at each advance of the cutting-block for the purpose above described, said platform is momentarily displaced by means 30 of cam-actuated mechanism, after the last lift has been cut and the operation of the cutting-block has been arrested, in order to permit the remaining waste end of the stock, if any is present, to be discharged from the 35 line of feed of a succeeding piece of stock. On account of this latter operation the platform 226 will hereinafter, for convenience, be termed the discharge platform. The cam-actuated mechanism above referred to 40 operates not only after the last lift has been cut but also after each successive cutting operation to modify the action of the discharge platform as the latter is displaced during the advance of the cutting-block. For this reason the construction of the 45 discharge platform, and the manner in which it is displaced to permit the cooperation of the die and the cutting-block, will be described later, in connection with the description of said cam-actuated mechanism and the manner in which the discharge platform is displaced thereby to effect the discharge 50 of the scrap.

When the stock has been fed into position 55 for the first cutting operation, the clutch 70 is operated automatically to rotate the cam sleeve 60 through a half revolution for the purpose of connecting the cutting-block with its actuating mechanism. The operation of the clutch 70 is controlled by a pair 60 of clutch controlling dogs 230 and 232 (Figs. 10, 12 and 18), the former being tripped to initiate the rotation of the cam sleeve 60 by mechanism including a sliding abutment or feeler 234 (Figs. 1, 2, 5 and 12), which is engaged and displaced by the

leading end of the stock as the latter reaches the farther end of the die. The clutch-controlling dog 232 brings the cam sleeve 60 to rest at the completion of the half revolution which is initiated by the tripping of the 70 dog 230.

The sliding abutment 234 consists of a bar which is dovetailed in the forward side of a slide 236 and rigidly secured thereto with provision for a longitudinal adjustment by means of screws 238 extending through longitudinal slots in the abutment bar 234 and into the slide 236. The slide 236 is provided with vertical guide-ribs 240 (Figs. 2 and 12) which are received in guideways 242 that are formed in a bracket 244 which is secured to the head 28, the guideways 242 being inclined rearwardly from the plane of the stock as the latter is fed across the die. Normally the slide 236 occupies the position in which it appears in Fig. 1, with the abutment 234 overlapping the adjacent cutting edge of the die and lying in the path of movement of the stock. The slide 236 carries a dog 246 (Figs. 1, 2 and 5), which is pivoted on a vertical stud 248, the dog projecting rearwardly from the slide and being received in an elongated slot 250 in the bracket 244. The dog 246 is normally held yieldingly, in the position shown in Figs. 1 and 2, by a spring 252, the outward movement of the dog under the influence of the spring being limited by a tail 254 which is arranged to engage the base of a recess in the slide 236 into which the tail extends. The dog 246 is adapted to engage a finger 256 which is secured to the upper end of a vertical rock-shaft 258 to the lower end of which the clutch-controlling dog 230 is secured. The rock-shaft 258 is adapted to oscillate in a bearing 260 which projects rearwardly from the bracket 244.

When the leading end of the stock which is being advanced by the feed rolls engages the sliding abutment 234, the latter is displaced toward the left side of the machine by means of the stock, causing the slide 236 also to move toward the left in its guideways. The dog 246 then engages and actuates the finger 256 to rock the shaft 258 and trip the clutch-controlling dog 230, thereby rendering the clutch 70 operative to rotate the cam sleeve 60.

The clutch 70 which is best shown in Figs. 10, 12, 13 and 18, comprises a driving clutch member 264 and a driven clutch member 266. The driving clutch member 264 consists of a disk (Fig. 13) which is secured to the vertical shaft 48 and is provided with a plurality of driving lugs 268 formed on its upper face. The driven clutch member 266 comprises a yoke which straddles a collar 270 which is adapted to turn on the shaft 48, above the driving clutch member 264, said

yoke being pivoted to the collar 270 by means of a stud 272. Integrally formed with the collar 270 and projecting upwardly therefrom is a bushing 274 (Fig. 13) which is interposed between the shaft 48 and the cam sleeve 60. The driven clutch member 266 is provided with a tongue 276 (Figs. 10, 12 and 18) that is adapted to cooperate with one or another of the driving lugs 268 on the driving clutch member. The driven clutch member 266 is engaged by one end of a spring 278, (Fig. 10) the opposite end of which bears against an ear 280 projecting from the collar 270, the force of the spring tending to depress the driven clutch member and maintains its tongue 276 in the path of rotation of one or another of the driving lugs 268.

While the cutting mechanism is inoperative, the driven clutch member 266 is maintained with its tongue 276 raised out of cooperative engagement with the driving lugs 268 by means of the clutch-controlling dog 230. After the dog 230 is tripped, the clutch members remain engaged only momentarily to cause the cutting-block to be connected with its actuating mechanism, the dog 232 disengaging the driven clutch member after the cam sleeve 60 has made a half revolution. While the cutting mechanism is operating, the driven clutch member is held out of engagement with the driving clutch member by the clutch-controlling dog 232 which is loosely mounted upon a vertical post 282 (Fig. 10) that is supported in the brackets 46. After the dog 232 is tripped, to cause the cutting-block and its actuating mechanism to be disconnected, the clutch members are engaged only during another half revolution on the cam sleeve 60, after which the clutch members are disengaged by the dog 230.

In order that the driven clutch member may be held out of engagement with the driving clutch member to maintain the clutch 70 inoperative, the two clutch-controlling dogs are severally provided with segmental lateral flanges 284, each concentric with the cam sleeve 60 and rising vertically from its respective dog into the path of rotation of the tongue 276 of the driven clutch member. The flange 284 has an upwardly inclined upper edge adapted to engage and raise the tongue 276 to rock the driving clutch member about its pivot stud 270 until it is disengaged from the driving lugs 268. Beyond the inclined upper edge of the flange 284 is a shoulder 286 which engages the side of the tongue 276 and arrests the rotation of the driven clutch member after the latter has been disengaged from the driving clutch member.

When the clutch-controlling dog 230 is tripped to cause the rotation of the cam sleeve 60, the cam 66, carried by the cam

sleeve, operates to render the cutting mechanism active. The cam lever 290 (Figs. 10 and 12) is pivotally mounted at one end upon the rock-shaft 258 and carries a cam roll 292 which rides on the periphery of 70 the cam 66, a spring 294 holding the cam roll against the cam. Pivoted to the outer end of the cam lever 290 is the rod 112 which normally holds the push bar 102 in inoperative position at one side of the lug 110 on 75 the plunger 90, and thus causes the push bar to reciprocate idly while the plunger 90 and the cutting-block 26 remain stationary.

In order to render the cutting-block operative, it is necessary to withdraw the rod 112 toward the left side of the machine so as to permit the spring 108 (Fig. 15) to swing the push bar 102 into position to engage the lug 110 of the plunger 90. When the rod 112 is withdrawn, a stop shoulder 85 111 (Fig. 5) on the lug 110 limits the angular movement of the push bar under the influence of the spring 108. During the half revolution of the cam sleeve 60, the cam 66 operates to thus withdraw the rod 112 and 90 after the push bar 102 has been positioned behind the lug 110, the advance of the push bar advances the plunger 90 and the cutting-block 26. Upon the rearward movement of the push bar 102, the spring 114 moves the 95 plunger and the cutting-block rearwardly.

During such time as the plunger 90 is idle, it is held against the action of the spring 114 in the position in which it is shown by dotted lines in Fig. 1 to provide clearance 100 between the rear face of the lug 110 on the plunger and the forward face of the push bar 102 by means of a detent 295 (Figs. 1 and 5). The detent 295 constitutes one arm of a bell-crank lever 296 (also shown in 105 Fig. 12) which is fulcrumed on the post 282, and the detent is normally seated in a notch 297 in the adjacent side wall of the plunger.

Upon the first advance of the plunger, the rear side wall of the notch 297 acts as a cam 110 to force the detent arm 295 out of the notch, and before the plunger 90 is retracted so as to return the notch into position opposite the detent, the latter is held in retracted position, as shown in Fig. 5, by means of 115 the cam 64 on the cam sleeve 60, said cam engaging a cam roll 298 carried by the other arm of the bell-crank lever 296. In this way the plunger 90 is permitted to follow its actuating link 102 rearwardly beyond the 120 position in which the plunger is maintained when idle, the lug 110 on the plunger remaining in contact with the link 102 throughout the entire extent of both the forward and rearward movements of the 125 latter so that the cutting-block will be reciprocated as smoothly as if it were positively connected with its actuating mechanism.

In order that the sliding abutment 234 130

shall not interfere with the advance of the scrap at the leading end of the stock the abutment is automatically moved toward the left in its guideway 242 immediately after the stock has been positioned for the first cutting operation. By reason of the incline of the guideway 242 this movement of the abutment causes it to be retracted toward the rear of the machine and out of the path 10 of the scrap.

The means for automatically retracting the abutment 234 from the line of feed of the scrap comprises a bell-crank lever 300 (Figs. 2, 10 and 12) which is actuated by 15 the cam 62 on the cam sleeve 60. The bell-crank lever 300 is pivotally mounted upon the post 282 and has a forwardly extending arm which is connected by a link 302 with an ear 304 projecting rearwardly from the 20 abutment slide 236. The other arm of the bell-crank lever 300 carries a cam roll 306 which is adapted to engage the periphery of the cam 62. A push spring 307 (Fig. 10) tends to hold the roll 306 against the cam 25 62 and thus position the abutment 234 in position to be engaged by the stock as it is fed across the die. During the first half revolution of the cam sleeve 60 the cam 62 actuates the lever 300 to move the abutment 30 slide toward the left, thus retracting the abutment rearwardly and out of the path of the scrap. As the abutment slide 236 moves toward the left under the influence of the cam 62, the dog 246 is moved out of engagement with the finger 258 and the clutch-controlling dog 230 is returned by means of a spring 308 (Fig. 10) to operative position, the spring 252 which acts upon the dog 246 permitting the latter to yield sufficiently to 40 allow the return of the finger 258.

Before introducing the stock into the machine, the main feed mechanism is adjusted to normally impart feed movements to the stock which are substantially equal in length to the width of the die. It will be seen by 45 reference to Fig. 1 that inasmuch as the feed rolls engage the stock at some distance from the near edge of the die, the first feed movement imparted to the stock will necessarily 50 be insufficient to advance the leading end of the stock completely across the die and into engagement with the abutment 234 and that the second feed movement of the feed rolls will ordinarily be more than sufficient to do 55 so. Consequently, in order to prevent over feed of the stock prior to the first cutting operation and resulting waste of stock, means is provided for arresting the rotation 60 of the feed rolls when the leading end of the stock has reached the far edge of the die.

The mechanism for arresting the rotation of the feed rolls, as best shown in Figs. 11 and 19, comprises a holding-pawl 312 65 which is adapted to engage the teeth of the

ratchet-wheel 164. These ratchet teeth, as shown, project radially from the ratchet-wheel 164, without any pitch, so that both the holding-pawl 312 and the feeding-pawl 166 which are oppositely directed, may operate at the proper time, the latter to rotate the ratchet-wheel and the former to arrest the rotation thereof. The holding-pawl 312 is secured to the lower end of a vertical shaft 314 (Fig. 11) which is journaled in a suitable bearing on the frame of the machine. Secured to the upper end of the shaft 314 is an arm 316 which is connected by a link 318 with the forward end of a lever 320 (Figs. 5, 10 and 12) that is pivotally mounted upon the post 282 and is acted upon by a push spring 322 (Fig. 10) tending to force the pawl 312 into yielding engagement with the teeth of the ratchet-wheel 164. Normally, however, a projection 324 (Fig. 19) on the rod 318 is engaged by a detent 326 which is pivotally mounted upon a fixed stud 328 and prevents the spring 322 from swinging the holding-pawl 312 into engagement with the ratchet-wheel 164. When, however, the lever 300 is actuated to retract the abutment 234, a lateral extension 330 of the detent 326 is engaged by a dog 332 which is pivotally mounted on the forwardly extending arm of the bell-crank lever 300 which actuates the abutment slide. The dog 332 is acted upon by a suitable light spring (not shown) which tends to hold it against a stop 334, in the position shown in Fig. 19. When the dog 332 engages the extension 330 the detent 326 is tripped thus permitting the spring 322 to swing the pawl 312 into holding engagement with the teeth of the ratchet-wheel 164. The yielding coupling 172-176 which is incorporated in the feed-roll actuating mechanism yields to permit the remainder of the feed movement of the feed-pawl actuating arm 178 to occur without interfering with the movement of the feed-pawl 166 or the ratchet-wheel 164. Before the completion of the first half revolution of the cam sleeve 60, the cam 68 operates through a cam roll 336 on the lever 320 to retract the holding-pawl 312, thus leaving the ratchet-wheel 164 free to rotate to impart the next feed movement to the feed-rolls. The detent 326 is then returned by means of a spring 338 into position to engage the projection 324 to hold the pawl 312 retracted, the light spring which acts upon the dog 332 yielding to allow the lateral extension 330 of the detent 326 to swing across the rear edge of the dog as the detent is restored into holding position.

In order that the rear end of the stock may be brought into such a position relatively to the die that a complete lift may be cut therefrom if the remaining piece of stock is large enough to produce a complete lift, means is provided for pushing the rem- 125 130

nant of the stock over the die as said remnant is released by the feed rolls. This means comprises an auxiliary feed device which is similar to a device employed for the same purpose in the machine of the aforesaid Baxter Patent No. 1,291,726. The auxiliary feed device of the present machine, in common with that of the Baxter machine, comprises a pair of pusher fingers 340, (Figs. 1, 4 and 17) which normally bear against the front face of the stock and are reciprocated idly toward and from the die. In their extreme position away from the die the forward ends of the pusher fingers 10 are so located as to engage the rear end of the last piece of stock to be fed over the die as this end is released by the feed rolls. The fingers 340 are received in transverse annular grooves 342 in the feed rolls (Figs. 15 20 and 16) the grooves in the forward feed roll 136 being deep enough so that when the stock is passing between the feed rolls, the pusher fingers may be depressed into the grooves in said feed roll against the tension 25 of a spring 344 (Fig. 4) connected to a projection 346 on one of the pusher fingers. The pusher fingers project integrally from a sleeve which is pivoted upon an oscillating support 348 fulcrumed at 350 upon the head 30 28, and is adapted to be oscillated to move the fingers toward and from the die.

The mechanism for operating the pusher fingers comprises a link 352 which is pivotally connected at its respective ends to the 35 support 348 and to an arm 354 upon a rock-shaft 356 which is suitably journaled in bearings on the frame of the machine, all as set forth in said Baxter patent. In the present construction, a second arm 358 on the rock-shaft 356 is connected by a link 360 with the forward end of a cam lever 362 (see Fig. 19) which is fulcrumed on the post 282. At the rear of the post 282 the cam lever 362 is provided with a cam roll 364 which is adapted 40 to engage a cam 366 on the main shaft 36. A spring 368 (Fig. 4) connected at one end to the arm 358 and at its opposite end to the portion of the head 28 tends to hold the cam roll 364 in engagement with the cam 366 and 45 to move the pusher fingers 340 in the direction to feed the stock. The cam 366 thus operates to move the pusher fingers positively in the direction of their return movement. A pair of slots is provided in the die-stripper 50 192, as best shown in Fig. 6, to permit the free extremities of the pusher fingers to occupy a position closely adjacent the side of the die. In this way the strip of stock will be so positioned by the auxiliary feed fingers 55 that the last lift will be cut at the extreme rear end of the stock and any waste that may remain will be located at the side of the die remote from the feed mechanism.

After the cutting mechanism has been rendered operative in the manner above de-

scribed, the cutting operation continues until the strip of stock which is being operated upon has become exhausted to such an extent that there is not enough material left to produce another complete lift. When this critical state of exhaustion occurs, the clutch controlling dog 232 is automatically tripped to initiate the second half revolution of the cam sleeve 60 for the purpose of disconnecting the cutting-block from its actuating mechanism. 70 The clutch-controlling dog 230 then arrests the rotation of the cam sleeve 60 after it has completed a half revolution. 75

The tripping of the clutch-controlling dog 232 to initiate the second half revolution of the cam sleeve 60 is effected by mechanism including a feeler 370 (Figs. 11 and 18) which is periodically and yieldingly advanced into the guideway 118 from the rear side thereof. The feeler 370 is normally prevented from completing its full stroke by the presence of a piece of stock within its field of operations in the guideway 118. Upon critical exhaustion of the stock, however, the feeler 370 is permitted to advance 80 through the full extent of its stroke and in so doing it trips the clutch-controlling dog 232 to operate the clutch 70 for the purpose of imparting the second half revolution to 85 the cam sleeve 60. 90

The feeler 370 consists of a rod which projects transversely with respect to the plane of the stock and is supported and guided for longitudinal movement in a bearing bracket 372 which is secured to a second bracket 374 (Figs. 4, 11 and 18) on the head 28 by means of screws 376 which extend through slots 378 in the bracket 372, the slots permitting adjustment of the feeler toward and from the die in accordance with the size of the lifts which are to be cut. To permit the feeler to be adjusted into close relation with the feed rolls, the stock engaging end of the former is offset laterally toward the feed rolls as shown in Fig. 18. The feeler is prevented 100 from turning in the bearing bracket 372 and thus varying the position of its stock engaging end by means of a pin 380 (Fig. 18) which is carried by a head 381 that is secured to the rear of the feeler, the pin 380 being received in a guideway 382 in the bearing bracket 372. 105 110 115

The feeler 370 is reciprocated by means comprising an arm 384 (Figs. 13 and 18) which is secured to the upper end of a vertical rock-shaft 386 that is suitably journaled in the frame. The arm 384 carries a roller 388 which is received in a groove 390 in the top of the head 381. To the lower end of the rock-shaft 386 is secured an arm 392 which is connected by means of a link 394 with one arm of a bell-crank lever 396 (Figs. 10, 18 and 19) the latter being fulcrumed on a post 398 carried by the lowermost of the brackets 46. The bell-crank lever 396 carries at the 120 125 130

end of its other arm a cam roll 400 that is adapted to be engaged by the periphery of the cam 50 that is secured to the shaft 48 and rotates continuously throughout the operation of the machine. A spring 402 tends to hold the roll 398 against the cam 50 and to yieldingly advance the feeler 370 into the guideway 118 when permitted by the cam.

The clutch control dog 232 is tripped, 10 upon the critical exhaustion of the stock to initiate the second half revolution of the cam sleeve 66 by means of a lug 406 (Fig. 18) which projects laterally from the link 394 into position to engage a tail 408 extending rearwardly from said clutch-control dog. So long as stock is present in the guideway 118 within the field of operations of the feeler 370, the feeler is prevented by the stock from moving through the full extent 20 of its stroke at each actuation thereof, and the lug 406 is prevented from engaging the tail 408. When the rear end of the stock has advanced beyond the feeler 370, the spring 402 is permitted to swing the cam lever 396 25 sufficiently to advance the feeler through the full extent of its movement, with the result that the lug 406 engages the tail 408, thereby tripping the clutch-controlling dog 232. The cam 70 then operates to impart the second half revolution to the cam sleeve 66.

During the second half revolution of the cam sleeve 66 the several cams carried thereby operate through the mechanisms associated therewith to restore the various operating instrumentalities controlled by said mechanisms to the positions which they occupied before the start of the first cutting operation. By means of the cam 66, the lever 290 and the rod 112, the plunger actuating 30 push bar 102 is swung to one side of the lug 110 on the plunger so that the plunger and the cutting-block are no longer actuated. When the plunger 90 is returned rearwardly by the spring 114 to the position in which it is shown in Fig. 1, the cam 64 operates the 35 detent arm 295 to lock the plunger against further movement to the rear in order to provide clearance between the lug 110 and the push bar 102 when the latter is again 40 swung behind the lug 110 to actuate the plunger 90. By means of the cam 62, the abutment slide 236 is restored to normal position with the sliding abutment 234 overlapping the die and yieldingly positioned in 45 the path of feed of the stock.

In order that the waste end of the stock which may remain after the last cutting operation, shall not interfere with the feed of a succeeding piece of stock, provision is 50 made for discharging said waste end from the line of feed. As already explained, this result is accomplished by momentarily displacing the discharge platform 226 from supporting position by means of cam-actuated 55 mechanism which operates after the cut-

ting of the last lift from a strip of stock, and while the cutting-block is maintained inoperative, thus allowing the waste end to fall from between the cutting-block and the die and be discarded. The construction of 70 the discharge platform and the manner in which it is displaced, both during the progress of the cutting operations to permit the advance of the cutting-block, and after the last lift has been cut to permit the discharge of the waste end, will now be described.

The discharge platform 226 (Figs. 6, 7, 8, 9 and 12) comprises a horizontal bar which is normally located in the vertical plane of 80 the stock, between the die and the cutting-block, and in a horizontal plane just beneath the lowermost point in the cutting edge of the die. The platform 226 is provided with a forwardly extending ear 412 which is secured to a horizontal stud 414 the opposite ends of which are pivotally mounted in the upper end of an oscillatory platform support 416. The platform support 416 comprises a pair of arms which rise integrally from a hub 418 (Fig. 9) and between which the ear 412 extends. The ear 412 has a downward extension 420 and is acted upon by a coiled spring 422, the force of which tends to hold the extension 420 against a 90 pin 424 which extends between the arms of the oscillatory support 416. The hub of the support 416 is pinned to a horizontal stud 426 the opposite ends of which extend through the bifurcated upper extremities of 100 a slide 428 (Fig. 9) which is mounted for vertical longitudinal adjustment in the horizontally reciprocating slide-block 194 which carries the die-stripper. For this purpose the slide 428 is provided with a pair of vertical guide-ribs 429 which are received in suitable guideways in the slide-block 194. A coiled spring 430, which surrounds a projecting end of the stud 426, tends to hold 105 the oscillatory support 416 in a substantially vertical position, a tail 432 (Fig. 6) at the bottom of said support normally engaging an adjacent portion of the slide 428 to limit the rearward tilting movement of said support under the influence of said spring.

As the cutting-block moves toward the die it engages a normally vertical face 433 at the rear side of the discharge platform 226 before it engages the stock, thereby oscillating the platform support 412 forwardly about the pivot stud 426. The discharge platform 226 is displaced forwardly without tilting until it strikes the bevelled edge 434 of the die whereupon the spring 422 permits the platform to tilt downwardly about the axis of the pivot stud 414 as the platform rides across said bevelled edge. When the cutting-block comes into engagement with the stock it forces the stock toward the die, thereby moving the die-stripper 192 and 110 120 125 130

the discharge platform 226 bodily toward the front of the machine. Substantially at the time the stock is forced against the cutting edge of the die the cam-actuated mechanism, above mentioned, becomes operative and acts in conjunction with the cutting-block to continue the forward movement of the die-stripper.

- 10 The cam-actuated mechanism for moving the die-stripper 192 and the discharge platform 226 comprises a horizontal push rod 438 (Figs. 6, 8, 9 and 12) the front end of which extends loosely into a socket 440 in the die-stripper slide-block 194. The push rod 438 extends rearwardly through a clearance opening in the head 28 and at its rear extremity is pivotally connected with one end of a cam lever 442 (Fig. 19) the opposite end of which is pivoted at 444 to the head 28. The cam lever 442 carries a cam roll 446 which rides upon the periphery of a cam 448 that is secured to the main shaft 36, the roll being held against the cam by the die-stripper springs 202.
- 15 The die-stripper 192 is first moved forwardly by the advance of the cutting-block independently of the push rod 438 which remains stationary, the loose socket connection between the forward end of the push rod 438 and the slide-block 194 permitting relative movements of said parts. As the cutting-block reaches the die, however, the forward end of the push rod is advanced into engagement with the base of the socket in the slide-block 194 and the cam 448 operates to continue the forward movement of the die-stripper until the latter reaches the position indicated by dot and dash lines in Fig. 8. During this additional movement of the die-stripper the spring 430 causes the discharge platform support 416 to swing rearwardly about the pivot stud 426 so that the discharge platform is maintained in position beneath the stock. As the cutting-block moves rearwardly the discharge platform support is returned to its normal vertical position with the tail 432 in engagement with the cooperating portion of the slide 428. The rearward or operative movement of the die-stripper 192 is effected by means of the springs 202, under the control of the cam 448, the cam causing the die-stripper to lag somewhat behind the cutting-block. During its rearward movement, the die-stripper strips the scrap from the die and finally returns the discharge platform to its normal vertical plane ready to support the leading end of a succeeding piece of stock.

20 When a piece of stock is positioned for the cutting of the last lift therefrom, the rear end of the stock may fall short of extending across the vertical die-stripper arm 192. In such a case, after the cutting of the lift, the rearward movement of the die-stripper will not engage the scrap to strip it

from the die. In order that the scrap may nevertheless be stripped from the die and discarded, the discharge platform is caused, at this particular time, to perform the function of a die-stripper.

25 In order to adapt the discharge platform to act as a die-stripper, a latch 450 (Figs. 6, 8 and 12) is pivoted at 452 to a forward extension of the slide 428, the latch having a hooked rear extremity which is adapted at 70 certain times to engage the pin 424 on the discharge platform support 416, as shown in Fig. 8. The latch 450 has a tail 454 depending from its pivoted end which carries a roller 456, and a spring 458 which is coiled 75 about the pivot 452 tends to lift the latch and hold the roller 456 against the vertical rear face of a stationary member 460 (Fig. 9) that rises from a portion of the frame of the machine. In a case where the stock has been so far exhausted that its rear end fails to extend across both the die and the die-stripper 192, the latter will not be moved as usual when the cutting-block engages the stock, but will remain stationary until it is 80 engaged by the cutting-block itself. Consequently, in the latter case, the discharge platform support 416 will be tilted by the action of the cutting-block through a greater number of degrees than when the stock extends across the die-stripper. The amount of excess tilting movement of the discharge platform support is sufficient to move the rear side of said platform to a position forward of the vertical plane of the front edge 85 of the stock. The latch 450 is so arranged that when the discharge platform support is tilted the usual amount, the pin 424 will not be swung forwardly far enough to be engaged by the latch, but when the stock fails to extend across both the die and the die-stripper the additional tilting movement imparted by the cutting-block to the discharge platform support will swing the pin 424 in front of the hooked end of the latch 450. 90 As the push rod 438 then advances the die-stripper, the pivot 452 of the latch is moved forwardly relatively to the stationary member 460 and the spring 458 maintains the roller 456 in contact with said member so that the latch 450 will be rotated in a direction to raise its hooked end in back of the pin 424, thus locking the discharge platform support in its extreme forwardly tilted position to prevent it from swinging rearwardly 95 upon the return of the cutting-block. The die-stripper 192 is prevented from moving rearwardly until after the cutting-block has started its rearward movement. When the retraction of the push rod 438 permits the die-stripper to move rearwardly, the latch 450 will be lowered, by reason of the coaction of the stationary member 460 and the roller 456 as the pivot 452 moves rearwardly, so 100 that the pin 424 will be released and the dis- 105

130

charge platform support will suddenly be swung rearwardly by the spring 430. During this swinging movement of the discharge platform support the spring 422 will cause the discharge platform, which is then positioned in front of the vertical plane of the stock, to ride across the bevelled edge 434 of the die and strip the scrap from the die. After being thus stripped from the die the scrap falls into a chute 462 (Figs. 6, 8, 9 and 12) which is supported upon the die-stripper block 194. The chute 462 guides the scrap to one side of the machine where it is discarded.

15 If, after critical exhaustion of the stock, the remaining piece is more than long enough to produce a complete lift, the discharge platform will be displaced in the same manner as during the cutting of the preceding lifts and thereafter returned to normal stock-supporting position. The next operation of the feed mechanism will operate upon the waste end of the stock which is too short to produce a complete lift, to advance it part way across the die. The cutting-block has, at this time been disconnected from its actuating mechanism and is maintained stationary, in its rearmost position, as already explained, and in order to provide for the discharge of said waste end, the discharge platform and the die-stripper are displaced bodily as a unit, by means of the cam-actuated push rod 438 which operates as usual. As soon as the discharge platform has moved from supporting position beneath the scrap, the scrap falls from the line of feed into the chute 462 and is discarded.

40 In order that the vertical adjustment of the discharge platform for different sizes of dies may be conveniently effected, the slide 428, on which said platform is mounted, is extended below the die-stripper slide-block 192 into a recess 464 in the head 28, as best shown in Figs. 9 and 17. The slide 428 is connected at its lower end by means of a short link 466 with the upper end of a vertical adjusting rod 468. The rod 468 is supported and guided for longitudinal adjustment in a suitable bearing in the head 28 and is screw-threaded into a bevel pinion 470 (see also Fig. 3). The pinion 470 meshes with a bevel pinion 472 which is secured to a horizontal shaft 474, the latter being adapted to turn in bearings in the forward standard 32. The shaft 474 extends through the standard 32 to the front of the machine where it is provided with a crank 476 (Figs. 1 and 3). By turning the crank 476 the vertical rod 468 may be raised or lowered to vary the elevation of the discharge platform. The link 466 and the recess 464 into which the lower end of the slide 428 extends permit said slide to move horizontally with the die-stripper as the latter is actuated to perform its stripping function.

Before a piece of stock which is being operated upon becomes completely exhausted, the operator introduces a second sheet in the guideway 118, advancing it manually in the direction of feed, in order that the cutting mechanism may operate upon the second sheet without substantial loss of time. It is obvious that if it were possible for the operator to keep a second piece of material so closely following the rear end of the piece which is being operated upon by the cutting mechanism that the auxiliary feed device would be prevented from engaging said rear end, the last mentioned strip would not be given the additional feed movement which is necessary to advance it completely across the die, and the feeler 370 would not be permitted to detect critical exhaustion of the stock. Accordingly, if a remnant of a strip of stock passes beyond the grip of the feed rolls which is more than large enough to produce a single complete lift, an incomplete or imperfect lift will be cut and forced into die upon the occurrence of the second successive cutting operation thereafter, said lift consisting of the waste portion at the rear end of the first strip and a portion of the succeeding strip.

In order to prevent the above described undesirable butting of strips of stock, a stop pin 480 (Figs. 1, 4 and 18) is provided, together with actuating mechanism therefor, whereby the stop pin is caused to penetrate the succeeding strip of stock for the purpose of temporarily arresting its advancing movement. When actuated, the stop pin holds the second strip from following the rear end of the first strip, thus permitting the auxiliary feed fingers to engage the rear end of the first strip to advance it across the die, and permitting the feeler 370 to detect exhaustion of the first strip in order that the cutting operation may be controlled in accordance therewith. Means is also provided for controlling or timing the penetrative movement of the stop pin so that it will occur after the machine has performed a predetermined number of cycles of operations, and a predetermined number of lifts have been cut from the piece of stock which is being operated upon, and also for timing the retraction of the stop pin from the succeeding strip of stock as soon as the danger of said strip interfering with the operation of the auxiliary feed finger and the feeler is passed.

With the exception of certain minor details, the stop pin 480, and the actuating and controlling mechanism therefor, are substantially the same in construction and mode of operation as the parts and mechanisms employed for the same purpose in applicant's copending application, Serial No. 342,656 (upon which Letters Patent No. 1,472,108 were granted Oct. 30, 1923). 130

In both the machines of the present application and of said prior Letters Patent No. 1,472,108, the temporary arrest of the advance of a succeeding strip of stock by means of the stop pin prevents said strip from interfering with the operation of the auxiliary feed fingers. While in the machine of said Letters Patent no feeler is employed for detecting exhaustion of the stock, it will be seen that the feeler of the present machine is actuated in a manner analogous to the mode of operation of a gate which is employed in the prior machine to control the presentation of the stock to the feed rolls. On account of the similarity of the stop pin actuating and controlling mechanism of the present machine to that of the prior machine only a brief and general description of the common features of the two sets of mechanism will be given, reference being had to the Letters Patent for a detailed description thereof.

Referring particularly to Figs. 17 and 18, the stop pin 480 is normally held retracted from the path of the stock and is adapted to be projected into the stock by the operation of bell-crank lever 484 which is connected to yieldingly advance the stop pin 480 toward the stock. The bell-crank lever 484 is secured to a rock-shaft 486 and the latter is adapted to be turned by means of a lever 488 (Fig. 11) which is rotatably and slidably mounted on the rock-shaft. In order that the lever 488 may actuate the rock-shaft 486 and still be free to slide thereon said lever embraces, at one end, a vertical rod 490 the upper and lower ends of which are secured to a pair of arms 492 which are pinned to said rock-shaft. The lever 488 is supported on the rock-shaft 486 by means of a follower arm 494 on which said lever rests and which is provided at its free end with internal thread segments adapted to engage with screw threads 496 externally formed on a sleeve (Fig. 17) that is secured to a continuously driven vertical shaft 498. The follower arm 494, which is pivotally mounted on the lever 488 so as to move vertically with the latter, is normally maintained by means of a suitable spring in operative engagement with the screw threads 496. The parts so far described are substantially the same as the corresponding parts described in the Letters Patent. In the present construction, the shaft 498, instead of being driven directly from the main shaft of the machine, is driven through an idler pinion 500 (Fig. 18) which meshes with the gear 54 on the main shaft 36 and with a gear 502 on the shaft 498. The rotation of the screw threads 496 raises the follower arm 494 and brings the lever 488 into the path of a roller 506 carried by a crank arm 508 which is secured to the shaft

498 and by which the lever 488 is engaged and oscillated to actuate the stop pin.

The stop pin is held in engagement with the stock as in the machine of the aforesaid patent, by means of a latch 510 (Fig. 18) which is pivoted at 512 to a fixed part of the machine and is spring pressed toward a lug 514 carried by one arm of the bell-crank lever 484 so that when the bell-crank lever is oscillated to project the stop pin into the stock a shoulder 516 on the latch 510 will move beyond said lug to prevent the bell-crank lever from returning to its normal position. As the lever 488 is oscillated by the crank arm 508 to actuate the stop pin, it engages a lug 518 (Fig. 11) on the follower arm and swings the latter out of engagement with the screw threads 496.

In the present construction, in order to insure against possibility of the screw threads 496 being injured by the downward movement of the follower arm, an annular flange 520 (Fig. 11) is provided on the roll 506 which is adapted to engage with the underside of a rib 522 on the lever 488. As the follower arm is disengaged from the screw threads, the flange 520 engages the underside of the rib 522 and temporarily prevents the follower arm from dropping before it has been retracted far enough to avoid striking against the screw threads. As soon as the roll 506 leaves the lever 488 the latter drops back to its normal position on the rock-shaft.

In common with the machine of the Letters Patent referred to, the downward movement of the lever 488 is limited by means of a stop device consisting of a bell-crank lever 524 (Fig. 3) and a cam 526 which is secured to a horizontal shaft 528. One arm of the bell-crank lever 524 is connected with a hub 530 that is formed on an arm 532 of the lever 488 so that the bell-crank lever 524 will be oscillated as the lever 488 slides up or down on the rock shaft 486. The other arm of the bell-crank lever 524 carries an adjustable projection 534 which is arranged to engage the periphery of the cam 526, a spring 536 tending to hold said projection against the cam.

In the present construction, the stop pin 480 is automatically retracted to release the stock by means of a ledge 540 on the upper portion of the head 381 that is carried by the feeler 370, this ledge 540 overlying a lug 542 on the latch 510. The ledge 540 is of sufficient length to insure that it will overlie said lug irrespective of the horizontal adjustment of the feeler toward or from the die. When the rear end of a piece of stock advances beyond the feeler 370 so that the latter moves through the full extent of its stroke at the next actuation thereof, the ledge 540 is moved forwardly an amount sufficient to engage the lug 542 and trip

the latch 510 to cause the stop pin to be retracted from the succeeding piece of stock.

After being disengaged from the screw threads 496, the follower arm 488 is held in retracted position by means of a latch 544, which is similar to the corresponding part in the machine of the Letters Patent. As therein set forth, the latch 544 comprises a plate having a vertically disposed edge 546 which is adapted to cooperate with an arm 548 which projects substantially at right angles from the follower arm 488, the vertical edge 546 extending through such a distance as to be adapted to engage the follower arm at any point within the range of vertical sliding movement of the latter so as to hold it disengaged from the screw threads 496. During the normal operation of the machine the arm 548 engages the side of the latch 544 and holds the latch inoperative, but when the follower arm is disengaged from the screw threads 496, the latch 544 swings in front of the arm 548 thereby latching the follower arm in disengaged position. In order to insure that the penetrative movements of the stop pin shall always occur at the proper time to engage the second strip of stock and prevent it from interfering with the operation of the feeler and the auxiliary feed fingers, provision is made whereby the cycles of operation necessary to actuate the stop pin will be always counted from the start of the feeding operations upon a new piece of stock. In other words, the follower arm 488, after being disengaged from the screw threads 496 is returned into engagement therewith concurrently with the start of feeding operations upon a new piece of stock. To this end the following provision is made for tripping the latch 544. As described in the aforesaid Letters Patent, the latch 544 is pivoted at 550 to one end of a lever 552 which is fulcrumed at 554 and carries a cam roll 556 at its opposite end. The cam roll 556 rides on the periphery of a cam 558 which, in the present machine, is secured to the shaft 498. By means of the cam 558 the pivoted end of the latch 544 is oscillated periodically about the fulcrum of the cam lever 552. A lug 560 projects from the latch, and after the stop pin has been retracted from the second piece of stock the lug 560 oscillates idly with the latch until said piece of stock is advanced in front of the feeler 370. Upon the next forward actuation of the feeler 370, it is prevented from moving through its complete stroke and the movement of the head 381 carried thereby is correspondingly modified. A rearward projection 562 on the arm 384, which oscillates with the head 381, is consequently maintained in the path of oscillation of the lug 560 on the latch 544, and when said lug strikes the projection 562

the latter serves as a fulcrum about which the latch 544 is rocked in a counter-clockwise direction in Fig. 18, so as to swing the latch 544 out of engagement with the arm 548 and thus permit the follower arm 488 to return into engagement with the screw threads 496. 70

In order to prevent the butting of strips at such a time that the second strip will interfere with the operation of the auxiliary feed fingers upon the first strip, and with the detection of exhaustion of the first strip by the feeler 370, the stop pin 480 must be actuated at some time after the leading end of the second piece of stock has been advanced beyond the stop pin and before the rear end of the piece of stock which is being operated upon has passed the feeler 370. To this end means is provided whereby the stop pin actuating mechanism may be set to 80 cause the actuation of the stop pin to occur during that cycle of operations of the machine which takes place while the rear end of the piece of stock which is being operated upon is located between the stop pin and the feeler. The setting of the stop pin mechanism is accomplished by adjusting the radial position of the cam 526. 90

The means for adjusting the cam 526, which is similar to the corresponding means of the aforesaid Letters Patent, comprises a crank arm 564 (Fig. 3) which is provided with a handle 566 and a suitable detent 568 which is spring-pressed to engage with a series of holes 570 in a segmental gage plate 572. The holes in the gage plate 572 are so spaced apart that by turning the handle 566 from one hole to another the normal position of the follower arm 488 may be shifted from one turn to another 100 of the screw threads 496. The operator, having first ascertained the number of cuts required for cutting once across the sheets of material which are to be operated upon, sets the stop pin actuating mechanism by 105 turning the handle 566 until the detent 568 engages the proper hole in the gage plate 572 to cause the stop pin to be actuated during the desired cycle of operations of the machine. 110

Although the sheets of stock from which the lifts are to be cut are intended to be of the same size, they are liable to vary somewhat in length due to different conditions during the drying of the stock, the difference being such that certain sheets of stock will produce one more lift to a row than the other sheets. In order that this variation in the size of the sheets of stock shall not vary the timing of the stock penetrating movement of the stop pin, the stop pin actuating mechanism is set in accordance with the maximum number of lifts which may be produced by cutting once across the sheets of stock to be operated upon, 125 130

which for example may be ten lifts. It will be seen that in cases where a sheet of stock will produce only nine lifts to a row the machine has to perform a complete cycle of operations to advance the scrap at the rear end of the piece of stock onto the discharge platform so that the scrap may be discarded. This last cycle of operations is counted by the stop pin timing mechanism the same as the preceding cycles during which the cutting operations occur. As a result the total number of cycles performed by the machine between the starting of the feeding operations upon a piece of stock and the projection of the stop pin into the stock will be the same whether the particular piece of stock produces nine lifts or ten lifts. In other words, so long as the variation in size between the sheets of stock operated upon is in no case greater than the width of one lift, the machine will perform the same number of cycles of operations upon the sheets of stock, following the start of the feeding operations thereupon, irrespective of the size of the sheets. By setting the stop pin actuating mechanism as above described, the production of the maximum number of lifts from each sheet of stock operated upon is insured.

While it is preferred to employ the specific construction and arrangement of parts shown and described, it will be understood that this construction is not essential, except so far as specified in the claims, and that it may be changed or modified without departing from the broader features of the invention.

The invention having been described, that which is claimed as new is:—

1. A machine of the character described having, in combination, initially idle means for operating on stock, feed mechanism for advancing the stock to the operating means, and means arranged to be engaged by an end face of the stock as it is advanced for controlling the action of the operating means.

2. A machine of the character described having, in combination, initially idle means for operating on stock, feed mechanism for advancing the stock to the operating means, and means dependent upon the position of the stock as it is advanced for controlling the action of the operating means and the feed mechanism.

3. A machine of the character described having, in combination, initially idle means for operating on stock, feed mechanism for advancing the stock to the operating means, and a feeler arranged to be engaged by the end of the stock projecting into the field of operations for starting the action of the operating means.

4. A machine of the character described having, in combination, initially idle means

for operating on stock, intermittently operative feed mechanism for advancing the stock to the operating means, and means for automatically arresting the feed of the stock and starting the action of the operating means.

5. A machine of the character described having, in combination, initially idle means for operating on stock, intermittently operative feed mechanism for advancing the stock to the operating means, and means for arresting the feed of the stock and starting the action of the operating means when the stock is located in position to be operated upon.

6. A machine of the character described having, in combination, initially idle means for operating on stock, feed mechanism for advancing the stock to the operating means, and means comprising members located one on each side of the operating means to be controlled respectively by the forward and rear ends of the stock as it is advanced for definitely determining the starting and stopping respectively of the operating means.

7. A machine of the character described having, in combination, means for operating on stock, feed mechanism for advancing the stock to the operating means, continuously acting driving mechanism normally disconnected from the operating means, and means, comprising a member arranged to engage an end face of the stock, for automatically connecting said driving mechanism to actuate the operating means.

8. A machine of the character described having, in combination, stock operating mechanism, means for feeding stock to the stock operating mechanism, continuously acting driving mechanism normally disconnected from said stock operating mechanism, means intermediate said stock operating mechanism and said driving mechanism for connecting and disconnecting said mechanisms, control means arranged to be movable in the path of the stock for controlling the operation of said intermediate means, and means for withdrawing the control means from the path of the stock after it has served its purpose.

9. A machine of the character described having, in combination, means for operating on stock, feed mechanism for advancing the stock to the operating means, continuously acting driving mechanism normally disconnected from the operating means, and means located beyond the operating means in the direction of feed of the stock for connecting the driving mechanism to actuate the operating means.

10. A machine of the character described having, in combination, means for operating on stock, feed mechanism for advancing the stock to the operating means, continuously acting driving mechanism normally

80

disconnected from the operating means, and means comprising a plurality of spaced stock engaging members for connecting said driving mechanism to actuate the operating means and for automatically disconnecting said driving mechanism from the operating means.

11. A machine of the character described having, in combination, means for operating on stock, feed mechanism for advancing the stock to the operating means, continuously acting driving mechanism normally disconnected from the operating means, means comprising a member arranged to project into the path of the operating means to engage the leading end of the stock for connecting said driving mechanism to actuate the operating means, and means dependent upon the state of exhaustion of the stock for automatically disconnecting said driving mechanism from the operating means.

12. A stock-cutting machine having, in combination, cutting means, feed mechanism for advancing a piece of stock to the cutting means, and means comprising a feeler arranged to project into the path of the cutting means to engage the stock for initiating the operation of the cutting means when the stock is properly located for the cutting operation.

13. A stock-cutting machine having, in combination, cutting means, feed mechanism for advancing a piece of stock to the cutting means, and means comprising a feeler arranged to engage an end face of the stock for initiating the operation of the cutting means.

14. A machine for cutting stock into blanks having, in combination, feed mechanism for advancing stock, means for cutting blanks successively from the stock as it is advanced, and means comprising two feelers one on each side of the cutting means for automatically starting the operation of the cutting means and for stopping the operation of the cutting means after a series of blanks have been cut.

15. A machine for cutting stock into blanks having, in combination, feed mechanism for advancing stock, means for cutting blanks successively from the stock as it is advanced, and means controlled by the stock for starting the operation of the cutting means and for stopping the operation of the cutting means after a series of blanks have been cut, said controlled means comprising a feeler arranged to project into the path of the cutting means to engage the advance end of the stock.

16. A machine for cutting stock into blanks having, in combination, feed mechanism for advancing stock, a cutter for cutting blanks successively from the stock as it

is advanced, means dependent upon the position of the leading end of the stock for starting the operation of the cutting means, and means spaced from the first-mentioned means and dependent upon the position of the rear end of the stock for stopping the operation of the cutting means.

17. A stock-cutting machine having, in combination, means for cutting blanks from stock, feed rolls for advancing a piece of stock to the cutting means, and means controlled by the stock for arresting the rotation of the feed rolls when the stock is properly located for the cutting of the first blank therefrom.

18. A stock-cutting machine having, in combination, cutting means, feed mechanism for advancing a piece of stock to the cutting means, and means controlled by the stock for arresting the feed of the stock and rendering the cutting means operative when the stock is properly located for the cutting operation.

19. A stock-cutting machine having, in combination, cutting means comprising a die, feed mechanism for advancing a piece of stock to the cutting means, a device constructed and arranged to overlap the edge of the die and to be displaced by the stock as the latter is advanced, and means controlled by said device for rendering the cutting means operative.

20. A machine for cutting stock into blanks having, in combination, cutting means, feed mechanism for advancing a piece of stock to the cutting means, a device constructed and arranged to be displaced by the stock as the latter is advanced for the first cutting operation, and means controlled by said device for arresting the feed of the stock when the stock has been properly located for the cutting operation.

21. A machine for cutting stock into blanks having, in combination, feed mechanism for advancing a piece of stock, means for cutting blanks successively from the stock as it is advanced, a device constructed and arranged to be displaced by the stock as the latter is advanced for the first cutting operation, and means controlled by said device for arresting the feed of the stock and for starting the operation of the cutting means when the stock is properly located for the cutting of the first blank therefrom.

22. A machine for cutting stock into blanks having, in combination, feed mechanism for advancing a piece of stock initially idle means for cutting blanks successively from the stock as it is advanced, a device constructed and arranged to be displaced by the stock as the latter is advanced for the first cutting operation and to locate the stock so as to insure the cutting of a perfect first blank therefrom, and means

controlled by said device for starting the operation of the cutting means when the stock has been thus located.

23. A machine for cutting stock into blanks having, in combination, cutting means, feed mechanism for advancing a piece of stock to the cutting means, means including an abutment normally positioned in the line of feed of the stock and adapted to be displaced substantially in the direction of feed of the stock to render the cutting means operative when the stock has been properly located for the first cutting operation, and means controlled by said abutment for arresting the feed of the stock when located by means of the abutment.

24. A machine for cutting stock into blanks having, in combination, cutting means, feed mechanism for advancing a piece of stock to the cutting means, means including an abutment normally positioned in the line of feed of the stock and adapted to be displaced substantially in the direction of feed of the stock to render the cutting means operative when the stock has been properly located for the first cutting operation, and means for subsequently retracting the abutment from the line of feed of the stock.

25. A stock-cutting machine having, in combination, feed mechanism for advancing a piece of stock, means for cutting blanks successively from the stock as it is advanced, means controlled by the piece of stock as it passes through the cutting plane or discontinuing the operation of the cutting means when the piece of stock has been exhausted to a predetermined extent and means for discharging the waste end piece of the stock.

26. A stock-cutting machine having, in combination, feed mechanism for advancing a piece of stock, means for cutting a series of perfect blanks successively from the stock as it is advanced, means for automatically discontinuing the operation of the cutting means in time to prevent the cutting of an imperfect blank, and means for discharging the waste end piece of the stock.

27. A stock-cutting machine having, in combination, feed mechanism for advancing a piece of stock, an abutment for locating the stock for the first cut movable out of the path of the stock, means for cutting blanks successively from the stock as it is advanced, and means including a feeler for detecting predetermined exhaustion of the piece of stock being cut for discontinuing the operation of the cutting means in accordance therewith, and for resetting the abutment in stock locating position.

28. A stock-cutting machine having, in combination, feed mechanism for advancing a piece of stock, means for cutting blanks successively from the stock as it is advanced,

and means including a feeler adapted to engage the stock repeatedly in timed relation to the cutting operations for determining exhaustion of the stock, said means being operative to discontinue the operation of the cutting means when there is not sufficient stock left in the piece being cut to form another perfect blank.

29. A stock-cutting machine having, in combination, feed mechanism for advancing a piece of stock, intermittently operating means for cutting blanks successively from the stock as it is advanced, means including a feeler for determining when the stock is so far exhausted that only one more perfect blank can be cut therefrom, and for rendering the cutting mechanism inoperative after the succeeding cutting operation, and means for discharging the waste end piece of the stock.

30. A stock-cutting machine having, in combination, feed mechanism for advancing a piece of stock, means for cutting blanks successively from the stock as it is advanced, comprising a die, a constantly reciprocating element and a movable connection between the die and its operating element and a feeler for engaging the stock as it is advanced and having connections to control the movable connection between the die and its operating element for discontinuing the operation of the cutting means when the stock has been exhausted to a predetermined extent.

31. A stock-cutting machine having, in combination, feed mechanism for advancing a piece of stock, initially idle mechanism for cutting successive pieces from the stock as it is fed, a movable support for the stock located adjacent to the cutting mechanism, and means for rendering the cutting mechanism initially operative only when the stock is properly positioned for the first cutting operation and for arresting the operation of the cutting mechanism when the stock has been so far exhausted that there is not enough left to produce another complete blank, said support being movable to discharge the waste end piece stock.

32. A machine for cutting stock into blanks having, in combination, feed mechanism for advancing a piece of stock, relatively movable cutting devices for cutting successive blanks from the stock as it is advanced, continuously reciprocable actuating mechanism arranged to be connected to relatively actuate the cutting devices, and means for automatically connecting said mechanism to effect said relative actuation.

33. A machine for cutting stock into blanks having, in combination, feed mechanism for advancing a piece of stock, relatively movable cutting devices for cutting successive blanks from the stock as it is advanced, continuously reciprocable actuating

mechanism, and means for connecting said mechanism to said cutting devices to relatively actuate the cutting devices and for automatically disconnecting said mechanism from the cutting devices to render them inoperative.

34. A machine for cutting stock into blanks having, in combination, feed mechanism for advancing a piece of stock, relatively movable cutting devices for cutting successive blanks from the stock as it is advanced, continuously operating actuating mechanism arranged to be connected to said devices for relatively actuating the cutting devices and to be disconnected from said devices to render them inoperative, and means arranged to project into the path of the relatively movable cutting devices and controlled by the position of the stock with respect to the cutting devices for connecting said mechanism to the latter and for disconnecting said mechanism therefrom.

35. A machine for cutting stock into blanks having, in combination, feed mechanism for advancing a piece of stock, a stationary die, a reciprocating cutting-block for cooperating with the die to cut successive blanks from the stock as it is advanced, actuating mechanism adapted to be automatically connected with the cutting-block to operate the latter and adapted to be automatically disconnected therefrom to render the cutting-block inoperative, and a feeler arranged to project over the edge of the die and controlled by the position of the stock with respect to the die for connecting the cutting-block with its actuating mechanism and for disconnecting it therefrom.

40. 36. A machine for cutting stock into blanks having, in combination, feed mechanism for advancing a piece of stock, a stationary die, a reciprocating cutting-block for cooperating with the die to cut successive blanks from the stock as it is advanced, actuating mechanism for the cutting-block comprising a connecting link constructed and arranged to be automatically connected with or disconnected from the cutting block, and means comprising feeler devices operating when the stock has been advanced into position to insure the cutting of a perfect first blank therefrom for connecting the cutting-block with its actuating mechanism and operating upon predetermined exhaustion of the stock to disconnect the cutting-block and its actuating mechanism.

37. A stock-cutting machine having, in combination, feed mechanism for advancing a piece of stock, means for cutting blanks successively from the stock as it is advanced, means controlled by the piece of stock being cut for arresting the operation of the cutting means at the proper time with respect to the piece being advanced by the

feed mechanism, and means for effecting the discharge from the field of operations of the cutting means of the portion of the stock remaining after the cutting means has become inoperative.

38. A stock-cutting machine having, in combination, feed mechanism for advancing a piece of stock, means for cutting blanks successively from the stock as it is advanced, a movable platform normally positioned to support the stock adjacent to the cutting means, means for arresting the operation of the cutting means, and means operating after the cutting means has become inoperative for displacing said platform to effect the discharge of the remnant of the stock from the line of feed.

39. A stock-cutting machine having, in combination, feed mechanism for advancing a piece of stock, a stationary die, a reciprocating cutting-block adapted to cooperate with the die to cut successive blanks from said piece of stock as it is advanced, means located between the die and the feed mechanism for stripping the scrap from the die, and auxiliary die stripping means rendered operative by the failure of the stock being operated upon to extend across the first-mentioned stripping means.

40. A stock-cutting machine having, in combination, a stationary die arranged with its cutting edge in a vertical plane, a reciprocating cutting block for cooperating with the die to cut blanks successively from a piece of stock, feed mechanism for advancing the stock into position to be operated upon, a die stripper between the die and the feed mechanism, and a movable platform normally positioned to support the leading portion of the stock and adapted to be displaced beneath the die as the cutting block advances and to return to normal strip-supporting position as the cutting block is retracted, and after the stock has become so far exhausted that it fails to extend across the die stripper to operate upon its next return movement to engage the strip produced by the last cutting operation and strip it from the die.

41. A machine for cutting stock into blanks having, in combination, initially idle cutting means, feed mechanism for advancing a piece of stock to the cutting means, means including an abutment normally positioned in the line of feed of the stock and adapted to be displaced substantially in the direction of feed of the stock to render the cutting means operative when the stock has been properly located for the first cutting operation, and means for subsequently retracting the abutment from the line of feed of the stock and for returning said abutment into normal operative position at the completion of the cutting operations upon said piece of stock.

42. A stock-cutting machine having, in combination, feed mechanism for advancing a piece of stock, means for cutting pieces successively from the stock as it is advanced, 5 an abutment normally positioned in the line of feed of the stock adapted to be displaced substantially in the direction of feed by the stock as the latter is advanced for the first cutting operation, and automatic means 10 rendered operative by the displacement of said abutment for controlling the operation of the cutting means and of the feed mechanism, and for withdrawing the abutment from the line of feed of the stock.
- 15 43. A stock-cutting machine having, in combination, feed mechanism for advancing pieces of stock successively presented thereto, means for cutting blanks successively from the stock as it is fed, means including 20 a feeler for detecting a predetermined exhaustion of the stock and controlling the operation of the cutting means in accordance therewith, said feeler being advanced in a direction transverse to the direction of 25 feed of the stock and normally prevented by the presence of stock within its field of operations from moving through the full extent of its stroke, and means for preventing a second piece of stock from following so closely the preceding piece as to prevent said feeler from performing its detecting operations.
44. A stock-cutting machine having, in combination, feed mechanism for advancing 35 pieces of stock successively presented thereto, means for cutting blanks successively from the stock as it is fed, means for detecting critical exhaustion of the stock, means controlled by said detecting means for rendering the cutting means inoperative, and means for preventing a succeeding piece of stock from following the preceding piece so closely that the detecting means will be prevented from performing its detecting operation.
45. A stock-cutting machine having, in combination, feed mechanism for advancing pieces of stock successively presented thereto, means for cutting blanks successively 50 from the stock as it is fed, means for detecting critical exhaustion of the stock, means controlled by said detecting means for rendering the cutting means inoperative, a holding device for preventing the advance of a second piece of stock from interfering 55 with the detecting operation of said detecting means, and means for retracting the holding device from the stock to permit the stock to be advanced to the feed mechanism.
- 60 46. A stock-cutting machine having, in combination, feed mechanism for advancing pieces of stock successively presented thereto, means for cutting blanks successively from the stock as it is fed, a feeler for detecting critical exhaustion of the stock, 65 means controlled by the feeler for rendering the cutting means inoperative, a holding device for preventing a second piece of stock from following the preceding piece so closely as to interfere with the detecting operation of the feeler, means for controlling the time of operation of the holding device, and means for rendering the holding device inoperative.
- 70 47. A stock-cutting machine having, in combination, feed mechanism for advancing pieces of stock successively presented thereto, means for cutting blanks successively from the stock as it is fed, a feeler for detecting critical exhaustion of the stock, 75 means controlled by the feeler for rendering the cutting means inoperative, and means operating after a predetermined number of cycles of operation of the machine for preventing the butting of a second piece of 80 stock against the rear end of the first piece, thereby permitting the feeler to perform its detecting operation.
- 85 48. A machine for cutting stock into blanks having, in combination, cutting means, feed mechanism for advancing a piece of stock to the cutting means comprising driving means therefor containing a yielding coupling, a device constructed and arranged to be displaced by the stock as 90 the latter is advanced for the first cutting operation, and means controlled by said device for arresting the feeding movement of the feed mechanism through the yielding of the coupling so that no further movement of the stock takes place after it has been properly located for the cutting operation.
- 95 49. A machine for cutting stock into blanks having, in combination, cutting means, feed mechanism for advancing a piece of stock to the cutting means, said mechanism comprising feed rolls for directly engaging the stock, pawl and ratchet mechanism for driving the feed rolls including a yielding coupling, a locking pawl 100 for engaging with the ratchet mechanism to prevent movement of the feed rolls in the feeding direction, a device constructed and arranged to be displaced by the stock as the latter is advanced for the first cutting operation, and connections between the device and the locking pawl for positioning the latter to stop the feeding movement of the rolls.
- 105 50. A machine for cutting stock into blanks having, in combination, cutting means, feed mechanism for advancing a piece of stock to the cutting means, driving mechanism comprising a clutch for connecting the cutting means to the source of power, a feeler arranged to contact with the stock and to determine exhaustion of the stock as the latter is advanced to the cutting means, and connections between the feeler and the 110

- 125
- 130

clutch to control the operations of the cutting means.

51. In a machine of the class described, feed mechanism for advancing a piece of stock, means for cutting blanks successively from the stock as it is advanced, a movable platform normally positioned to support the stock adjacent to the cutting means, means for arresting the operation of the cutting 10 means, and a plunger, operating after the cutting means has become inoperative, for displacing the platform to effect the discharge of the waste end piece of the stock from the line of feed.

52. In a machine of the class described, feed rolls intermittently operative for advancing a piece of stock, relatively movable die and block members for cutting blanks successively from the stock, a movable platform normally positioned to support the stock adjacent to the cutting means, a feeler 20 operable to feel for the stock and having connections to stop the relative cutting movements of the die and block when the stock 25 is exhausted, and a plunger operable subsequently to the last cutting operation for moving the platform away from supporting position so that the waste end of the stock is discharged from the line of feed.

53. In a machine of the class described, feed rolls for advancing a piece of stock, relatively reciprocable die and block members for cutting blanks from the stock, a movable platform normally positioned to support the stock adjacent to the cutting means, a stripper for removing the waste stock from the die, said platform and stripper being movable to discharge a waste end piece when the latter is large enough to engage the stripper, and a plunger for operating the platform and stripper as a unit to discharge waste end pieces of the stock which are not large enough to engage the stripper.

54. In a machine of the class described, a die for cutting blanks from stock, a cutting block reciprocable toward and from the die, feed mechanism for feeding stock to the die, a main shaft, a clutch between the main 50 shaft and the cutting block, a feeler arranged in the path of the stock to be engaged thereby to position the stock for the first cutting operation, and connections between the feeler and the clutch for controlling the 55 reciprocations of the block so that no cutting operation takes place until the work is properly located over the die.

55. In a machine of the class described, a die, a cutting block reciprocable toward 60 and from the die in cutting operations upon stock, a main shaft, a clutch between the main shaft and the cutting block, feed mechanism for advancing the stock into cutting position with respect to the die comprising a yielding coupling between the main shaft

and the stock engaging part of the feed mechanism, a lock for the feed mechanism, and means controlled by the work for determining the time of operation of the clutch and of the lock so that the feeding 70 and cutting operations will be performed at the proper times to cut complete blanks from the stock.

56. In a machine of the class described, a die, a cutting block reciprocable toward 75 and from the die in cutting operations upon stock, a main shaft, a clutch between the main shaft and the cutting block, feed mechanism for advancing the stock into cutting position with respect to the die comprising 80 a lock for the feed mechanism, and a pair of feelers for engaging the stock and arranged to control the clutch and the lock so as to ensure properly timed cutting and feeding operations with the stock in proper 85 position for cutting complete blanks.

57. In a machine of the class described, feed mechanism for advancing a piece of stock, a stationary die, a reciprocable cutting block adapted to co-operate with the 90 die to cut successive blanks from the piece of stock, a stripper associated with the die for stripping the scrap therefrom, and a platform normally operative to support the stock for cutting operations and movable 95 with the stripper to discharge waste pieces of stock from the path of feed of the stock.

58. In a machine of the class described, feed mechanism for advancing pieces of stock successively presented thereto, a cutter 100 for cutting blanks from the stock, a feeler for detecting critical exhaustion of the stock, means controlled by the feeler for rendering the cutter inoperative, means for discharging the waste end of the stock, a holding device for preventing a second piece of stock 105 from following the preceding piece so closely as to interfere with the detecting operation of the feeler, and means for rendering the holding device inoperative so that the second piece of stock may follow the preceding piece in properly timed relation.

59. In a machine of the class described, feed mechanism for advancing pieces of stock successively presented thereto, a cutter 115 for cutting blanks from the stock, a feeler for detecting critical exhaustion of the stock, a clutch controlled by the feeler for rendering the cutter inoperative, a platform normally operative to support the stock and movable to discharge the waste end of the stock, and a holding device for preventing a second piece of stock from following the preceding piece so closely as to interfere 120 with the detecting operation of the feeler, said holding device being rendered inoperative at the proper time for feeding in the second piece.

60. In a cutting machine, means for supporting sheet material while it is being op- 130

erated upon, and means for causing relative movement of the material and a die to cut blanks from the material, said means comprising a block and a constantly reciprocable member arranged to be intermittently connected to the block to cause operative strokes of the latter.

61. In a machine of the character described, means for cutting blanks from stock, feed mechanism for advancing a piece of stock to the cutting means, and means engaging the piece of stock for initiating operations of the cutting means when the piece of stock has been fed into operative position for cutting the first blank therefrom and for

rendering the cutting means inoperative when the last complete blank has been cut from the piece of stock.

62. In a machine of the class described, cutting means comprising a stationary die mounted with its cutting edge in a vertical plane and a vertically disposed cutting block adapted to reciprocate horizontally toward and from the die, means for feeding sheet material in a vertical plane to the cutting means, and means for separating the sheet material into strips as it is fed to the cutting means.

ERASTUS E. WINKLEY.
